Primary Examiner — Rosemary K Tarcza(74) *Attorney, Agent, or Firm* — Holland & Hart LLP(57) **CLAIM**

The ornamental design for a charging station, as shown and described.

DESCRIPTION

FIG. 1 is a front perspective view of the charging station, showing my new design;

FIG. 2 is a front view of the design illustrated in FIG. 1; FIG. 3 is a rear view of the design illustrated in FIG. 1; FIG. 4 is a right view of the design illustrated in FIG. 1; FIG. 5 is a led view of the design illustrated in FIG. 1; FIG. 6 is a top view of the design illustrated in FIG. 1; and, FIG. 7 is a bottom view of the design illustrated in FIG. 1. The broken lines in the drawings are for the purpose of illustrating portions of the charging station that form no part of the claimed design.
